UNITED STATES PATENT OFFICE.

GEORGE A. GREEN, OF DUXBURY, MASSACHUSETTS, ASSIGNOR TO JOHN S. WRIGHT, OF SAME PLACE.

MACHINE FOR PERFORATING STRIPS OF PAPER.

SPECIFICATION forming part of Letters Patent No. 683,687, dated October 1, 1901.

Application filed March 28, 1901. Serial No. 53,248. (No model.)

To all whom it may concern:

Be it known that I, GEORGE A. GREEN, a subject of the King of Great Britain, residing at Duxbury, in the county of Plymouth and State of Massachusetts, have invented 5 new and useful Improvements in Machines for Perforating Strips of Paper, of which the following is a specification.

The object of this invention is to produce 10 a machine for perforating strips of paper such as are used in telegraphy for transmitters in connection with the "Wheatstone" and "siphon-recorder" or other systems and also for perforating strips of paper such as 15 are used in musical instruments, &c.

The object of this invention is, further, to produce a machine for performing the functions hereinbefore recited with great speed, and which may be operated by persons 20 entirely ignorant of the telegraphic operator's art.

The invention consists in a machine for perforating a strip of paper comprising mechanism for imparting an intermittent feeding 25 motion to said strip of paper, a series of punches arranged to perforate said strip of paper, a series of levers arranged to actuate said punches, and a series of electromagnets in circuit with said levers in combination with 30 a make-and-break device operated by a bank of keys, whereby said levers are actuated through said electromagnets to operate said punches and perforate said strip of paper.

The invention further consists in the combination and arrangement of parts set forth 35 in the following specification and particularly pointed out in the claims thereof.

Referring to the drawings, Figure 1 is a plan view of my improved machine for perforating strips or ribbons of paper. Fig. 2 is an enlarged vertical section taken on line 2 2, Fig. 1, looking toward the right in said figure. Fig. 3 is an enlarged vertical section, partly in elevation, taken on line 3 3, 40 Fig. 1, illustrating the perforating mechanism. Fig. 4 is a detail plan view of the perforating mechanism. Fig. 5 is a detail end elevation of the strip-perforating punches. Fig. 6 is a detail view of a strip of paper 45 perforated for a siphon-recorder strip.

Like numerals refer to like parts throughout the several views of the drawings.

The machine of this invention consists as a whole, first, of a machine 10 for perforating a strip of paper 11, said machine, as 55 hereinafter described, being substantially the same in construction as the hand-operated perforating-machines used in perforating strips of paper used in the Wheatstone system, but differs therefrom in being operated by a battery in circuit therewith, and, second, of a device 14 for making and breaking circuit with said perforating-machine. The make-and-break device 14 is inclosed in a casing 15, provided with doors 16 to provide 60 access to the interior thereof. Upon the exterior of the casing 15 is a series of keys or knobs 17, arranged in banks. Said keys are fast to vertical reciprocating rods 18, preferably square in cross-section and arranged to slide in guides 19, fast to the top of the casing 15, and in guides 20, formed in the guide-plate 21. The guide-plate 21 is supported upon a central standard 22, having a base 23, fast to the bottom of the casing 15. The lower ends of the rods 18 are cylindrical and are screw-threaded to receive the nuts 24, said nuts forming stops to limit the upward movement of said rods. Felt or leather washers 25 encircle the rods 80 18 below the keys 17 and above the nuts 24 to deaden the noise which would otherwise be caused by the keys striking the top of the casing at the end of the downward movement of the rods or by the nuts 24 striking the under side of the guide-plate 21 at the end of the upward movement of said rods. The rods 18 are forced downwardly by the pressure of the operator's finger upon the keys 17, and when said pressure is released the rods are 85 carried up to their normal position by a double flat spring 26, fastened at its central portion to the base 23 by screws and having its free ends curved and forked to form claws 27, which press firmly against studs or pins 28, 90 fast to the cylindrical portion of the rods 18 and forming a metallic contact with said rods.

To the side of each of the rods 18 is adjustably fastened a flat spring 29, curved outwardly in the form of an ogee from said rod 100

and provided with a platinum contact-point 30 at its free end. In each of the springs 29 is formed a slot 31, the upper edge thereof being inclined toward the rod 18 and arranged 5 to engage a spring-catch 32, adjustably fastened to said rod. When the rod 18 is depressed, the curved portion thereof engages the cam-shaped surface 33 upon a vertical flange 34 on the guide-plate 21, forcing said 10 spring inwardly toward the rod 18 until it engages the catch 32, and is held thereby in the position shown at the right of Fig. 2. When the pressure upon the key is released, the spring 26 carries the rod 18 upwardly from 15 the position in which the rod at the right of Fig. 1 is shown to that in which said rod is shown at the left of said figure, and at the end of said upward movement the spring-catch 32 strikes against the stop 35, fast to 20 the under side of the top of the casing, and is thus forced downwardly at its outer end with relation to said rod and releases the contact-spring 29, which snaps outwardly at its free end from said rod until the contact-point 30 25 thereon abuts against a vertical block 36 of ebonite or other insulating material fast to the under side of the top of the casing 15. Upon the face of the ebonite block 36, adjacent to the rods 18, are embedded platinum 30 contact-points 37 38 39, each point connected by an independent wire to a binding-screw 40, thence by independent wires 41 42 43 to electromagnets 44 45 46, the electromagnets being connected by the wire 47 to the battery 35 48 and the battery connected by the wire 49 to the base 23.

The perforating-machine 10, shown in Figs. 3 and 4, may be of any suitable construction. In this case said perforating-machine is substantially the same as the Wheatstone perforator in the principle of its operation, the same being arranged to perforate a "Thompson siphon - recorder" slip, as illustrated in Fig. 6. The strip of paper 11 to be perforated is fed forward by a toothed feed-wheel 50, and holes are punched therein, as shown in Fig. 6, by the punches 51, 52, and 53. Said punches are arranged in the same vertical plane and slide in bearings in the guide-plate 57, being held out of contact with the paper 11 by springs. The punches 51, 52, and 53 are forced through the strip of paper 11 by the levers 58, 59, and 60. Said levers are pivoted to the frame of the perforator at 55 61 and are actuated by the electromagnets 44, 45, and 46, respectively. The perforating-machine 10 is so constructed and arranged that the lever 58 upon being actuated by the electromagnet 44 will force the punches 51 60 and 52 through the paper and punch a hole in the upper and middle rows of the three rows of perforations in the strip of paper shown in Fig. 6. The lever 59 is actuated by the electromagnet 45 and forces the punch 52 65 through the paper, making a hole in the middle row of perforations, and the lever 60 is actuated by the electromagnet 46, forcing

forward the punches 52 and 53, and thus making a hole in the middle and lowermost rows of the three rows of perforations in the strip 70 11. The middle row of perforations is used to feed the paper forward by means of the toothed feed-wheel 50, actuated by a pawl 62, pivoted to a lever 63, said lever pivoted to an arm 64, arranged to rock upon a pivot 65, 75 fast to the frame 66, the arm 64, lever 63, and pawl 62 being held in the position shown in Fig. 4 by a spring 67, connected to the lever 63 by a link 68.

It will be seen that any letter desired may 80 be obtained by supplying the proper number of contact-points 37, 38, and 39 upon the ebonite block 36 and connecting said contact-points to the wires 41, 42, and 43, so that when the circuit is made the levers 58, 59, 85 and 60 will be actuated to force the punches 51, 52, and 53 through the paper strip 11 in the order and in the relative location desired. Take, for instance, the letter "A," Fig. 6. The first contact-point 37 is connected to the 90 binding-screw 40 and thence to the wire 41. The second contact-point would be connected to the wire 43 and the third contact-point to the wire 42. When the contact-point 30 made contact with the point 37, the electromagnet 95 44 would actuate the lever 58 and force the punches 51 and 52 through the paper 11. As soon as the circuit is broken by the contact-point 30 leaving the contact-point 37 the lever 58 returns to its normal position, the 100 punches 51 and 52 are withdrawn from the paper, and the paper strip 11 is fed one space. The contact-point 30 next makes contact with the contact-point 38, and the lever 60 is actuated by the electromagnet 46, thus 105 forcing the punches 52 and 53 through the paper, and upon the breaking of the circuit by the further depression of the contact-point 30 said lever 60 returns to its normal position, the punches 52 and 53 are withdrawn 110 from the paper, and the paper is fed another space. Finally, the contact-point 30 engages the contact-point 39 and the lever 59 forces the punch 52 through the paper, and upon the circuit being broken the said lever 59 returns to its normal position and the punch 52 115 is withdrawn from the paper. Thus in one depression of the key 17 the paper strip 11 is perforated for the letter "A" and for the space between said letter "A" and the following letter, as indicated in Fig. 6. The letters "B" "C," &c., are perforated in a similar manner by arranging the contact-points upon the ebonite block 36 in the proper relation to each other to operate the levers 58, 59, 120 and 60 and the punches 51, 52, and 53, as desired. Each letter in the bank of keys has an ebonite block, with contact-points thereon of the proper number and connected to the levers 58, 59, and 60 to actuate the punches 125 51, 52, and 53 at the proper time and in the proper relation to each other to perforate the strip of paper as may be desired. By reference to the strip of paper, Fig. 6, it will be 130

seen that any combination of perforations therein shown may be obtained by the three punches 51, 52, and 53, arranged in a vertical line one above the other, the punches 51 and 52 being operated by one lever, the punch 52 alone by another lever, and the punches 52 and 53 by the third lever. A key 54, Fig. 1, is provided for spacing between the words.

Having thus described my invention, what 10 I claim, and desire to secure by Letters Patent, is—

1. A machine for perforating a strip of paper comprising mechanism for imparting an intermittent feeding motion to said strip of paper, a punch arranged to perforate said strip of paper, a lever arranged to actuate said punch, an electromagnet in circuit with said lever, a stationary contact-point, a reciprocatory rod, a contact-spring carried by said 20 rod, and means for holding said contact-spring out of contact with said stationary contact-point during the movement of said rod in one direction.

2. A machine for perforating a strip of paper, comprising mechanism for imparting an intermittent feeding motion to said strip of paper, a punch arranged to perforate said strip of paper, a lever arranged to actuate said punch, an electromagnet in circuit with 25 said lever, a stationary contact-point, a reciprocatory rod, a contact-spring carried by said rod and arranged to engage said contact-point during the movement of said rod in one direction, and means for holding said contact-spring out of contact with said stationary contact-point during its movement in the opposite direction.

3. A machine for perforating a strip of paper comprising mechanism for imparting an intermittent feeding motion to said strip of paper, a punch arranged to perforate said strip of paper, a lever arranged to actuate said punch, an electromagnet in circuit with 40 said lever, a stationary contact-point, a reciprocatory rod, a contact-spring carried by said rod, a slot in said contact-spring, a spring-catch fast to said rod arranged to enter said slot, and means to force said contact-spring into and out of engagement with said spring-catch.

4. A machine for perforating a strip of paper comprising mechanism for imparting an intermittent feeding motion to said strip of paper, a punch arranged to perforate said strip of paper, a lever arranged to actuate said punch, an electromagnet in circuit with 55 said lever, a stationary contact-point, a reciprocatory rod, a contact-spring carried by said rod, a slot in said contact-spring, a spring-

catch carried by said rod arranged to enter 60 said slot, and a stationary flange arranged to engage said contact-spring when said reciprocatory rod is moving downwardly and force said contact-spring into engagement with said spring-catch.

5. A machine for perforating a strip of paper comprising mechanism for imparting an intermittent feeding motion to said strip of paper, a punch arranged to perforate said strip of paper, a lever arranged to actuate 70 said punch, an electromagnet in circuit with said lever, a stationary contact-point, a reciprocatory rod, a contact-spring carried by said rod, a slot in said contact-spring, a spring-catch carried by said rod arranged to enter 75 said slot, and a stationary flange arranged to engage said contact-spring when said reciprocatory rod is moved downwardly and force said contact-spring into engagement with said spring-catch, and a stationary stop arranged 80 to engage said spring-catch upon its upward movement and disengage the same from said contact-spring.

6. A machine for perforating a strip of paper comprising mechanism for imparting an 85 intermittent feeding motion to said strip of paper, a series of punches arranged to perforate said strip of paper, a series of levers arranged to actuate said punches, a series of electromagnets in circuit with said levers, a 90 series of stationary contact-points, a reciprocatory rod, a contact-spring carried by said rod, and means for holding said contact-spring out of contact with said stationary contact-points during its movement in one direction.

7. A machine for perforating a strip of paper comprising mechanism for imparting an intermittent feeding motion to said strip of paper, a series of punches arranged to perforate said strip of paper, a series of levers arranged to actuate said punches, a series of electromagnets in circuit with said levers, a 100 series of stationary contact-points, a reciprocatory rod, a contact-spring carried by said 105 rod and arranged to engage said contact-points during the movement of said rod in one direction, and means for holding said contact-spring out of contact with said stationary contact-points during its movement in the opposite direction.

In testimony whereof I have hereunto set my hand in presence of two subscribing witnesses.

GEORGE A. GREEN.
